INTERNAL COMBUSTION ENGINE RADIO FREQUENCY RADIATION SUPPRESSING IGNITION SYSTEM

This application is a Continuation-in-Part of pending U.S. Pat. application Ser. No. 761,193, filed Sept. 20, 1968 now abandoned.

This invention relates to internal combustion engine ignition systems and, more specifically, to an ignition system of this type which suppresses radio frequency electromagnetic energy radiation.

In all internal combustion engines, electromagnetic energy of a radio frequency is radiated from the distributor, the ignition cable and the spark plugs of the associated engine. This electromagnetic radiation is very undesirable as it seriously interferes with the reception of nearby radio receivers.

Several arrangements and methods have been developed heretofore in an effort to decrease this radiated energy, however, most have been found to be unsatisfactory. Although the magnitude of this radiated energy is considerably reduced by the use of resistor type spark plugs and television-radio suppression ignition cable, a greater suppression of this radiation is desirable.

It has been found that a considerably greater reduction of radiated radio frequency energy, 20 to 50 decibels has been measured in the range of 100 to 1,000 megacycles, is realized by providing a distributor having the air gap between the rotating terminal and each stationary terminal of a width which is greater than is currently normal. This phenomena is observable initially at the higher frequencies, in the order of 1,000 megacycles, and, as the gap is increased, a greater suppression is realized toward the lower end of the frequency spectrum.

It is, therefore, an object of this invention to provide an improved internal combustion engine radio frequency radiation suppressing ignition system.

It is another object of this invention to provide an improved internal combustion engine radio frequency radiation suppression system wherein a wide distributor gap is employed in combination with resistor type spark plugs and television-radio suppression ignition cable.

In accordance with this invention, an improved internal combustion engine radio frequency radiation suppressing ignition system is provided wherein a wider than normal distributor gap is employed in combination with resistor type spark plugs and television-radio suppression ignition cable.

For a better understanding of the present invention together with additional objects, advantages and features thereof, reference is made to the following description and accompanying drawing, in which:

FIG. 1 schematically sets forth the ignition system of this invention; and

FIG. 2 is a bottom view of the distributor cap of FIG. 1.

The internal combustion engine radio frequency radiation suppressing ignition system of this invention comprises a resistor type spark plug for each cylinder of the internal combustion engine with which the ignition system is to be used, an ignition distributor having a stationary terminal corresponding to each spark plug and a movable terminal rotated in timed relation with the engine and positioned to successively pass closely adjacent to each of the stationary terminals, a television-radio suppression ignition cable extending between each stationary terminal and the corresponding spark plug and an air gap between the ignition distributor movable terminal and each stationary terminal of a width within the range .060 inch to .250 inch at the point of nearest approach.

A resistor type spark plug of a resistance valve compatible with the associated engine, for example of a value within a range of 1,500 to 50,000 ohms, is provided for each cylinder of the internal combustion engine with which the ignition system is to be used. In FIG. 1 of the drawing, which sets forth the ignition system of this invention for a 6 cylinder internal combustion engine, one resistor type spark plug 10 is shown partially in cross section while the remainder of the spark plugs are schematically illustrated and referenced 10a, 10b, 10c, 10d and 10e. The resistor type spark plug includes a shell 75

11 provided with screw threads at its lower end, for threaded connection with the engine, a ground electrode 12 secured to its lower edge and a stepped centerbore 13 forming an internal ledge 14 therein. Positioned upon ledge 14 is an insulator sleeve 15 of a ceramic material which is secured in gas tight relationship with ledge 14. The insulator sleeve 15 is provided with a stepped centerbore 16 to receive and position a center electrode. Positioned in the centerbore overlaying the center electrode 17 is the resistor section 18 which is in electrical contact with electrode 17. An upper conductive seal 19 and a lower conductive seal 20 provide a gas tight seal relationship within insulator 15. An upper center electrode 21, in electrical contact with upper seal 19, provides for an electrical connection to an ignition cable. Spark plugs of this type are currently commercially available, one specific type being disclosed and described in U.S. Pat. No. 3,235,655 which issued Feb. 15, 1966 and is assigned to the assignee of the present invention.

A conventional ignition distributor 25, shown partially in cross section and partially in cutaway, includes a bowl portion 26, a rotor member 27, a shaft 28, which is gear connected to the cam shaft of the associated internal combustion engine, and a distributor cap 29. A movable terminal 30 is secured to rotor 27, and, consequently, is rotated in timed relationship with the engine therewith. A stationary terminal corresponding to each spark plug of the engine, referenced by numerals 31a, 31b, 31c, 31d, 31e and 31f, in FIG. 2, is provided. Movable terminal 30 of the distributor is positioned to successively pass closely adjacent to each of the stationary terminals, the distance between the end of the movable terminal and each stationary terminal at the point of nearest approach being an air gap 32 which will hereinafter be referred to as the distributor gap.

Extending between each stationary terminal of distributor 35 and the corresponding resistor type spark plug is a television-radio suppression ignition cable hereinafter referred to as "TVRS" ignition cable. Ignition cable of this type is commercially available in a range of resistance values between 2,000 and 10,000 ohms per foot and is comprised of a plurality of straight parallel threads 35 covered by a sheath of braided threads 36 which are impregnated with a suitable carbonaceous material such as graphite and enclosed by a first insulating sheath 37 and a second insulating sheath 38. Although only the cable connected between stationary terminal 31a and the distributor and resistor spark plug 10 is shown in detail in the drawing, it is to be specifically understood that the ignition cables extending between each other stationary terminal and the corresponding spark plug is of the same "TVRS" type. Ignition cable of this type is disclosed and described in U.S. Pat. No. 2,714,623 which issued Aug. 2, 1955 and is assigned to the assignee of the present invention.

The secondary winding, not shown, of a conventional ignition coil 45, which is effective during engine operation for producing a high potential pulse when each spark plug is to be energized, is connected to the movable terminal 30 of the ignition distributor 25 through ignition cable 41, which is also of the "TVRS" type, center terminal 40 and spring contact 42, in a conventional manner.

It has been found that a considerable reduction of electromagnetic radiation of a radio frequency may be realized by extending distributor gap 32 to a width greater than is currently normal in automotive type engines. The ignition potential magnitude induced in the secondary winding of the ignition coil, of course, determines the maximum width of distributor gap 32 as this energy must cross this gap to provide ignition potential across center electrode 17 and ground electrode 12 of each spark plug. Distributor gaps within a range of .060 inch to .250 inch in combination with "TVRS" ignition cable and resistor type spark plugs have provided a radio frequency radiation suppression of substantially 100 percent.

In a typical specific application of the combination of the present invention, the distributor 25 was mounted upon the internal combustion engine with the "TVRS" ignition leads ex-

tending varying distances up to approximately 24 inches from the stationary contacts thereof to the respective spark plugs. Each of the "IVRS" ignition leads had a resistance value of approximately 4,000 ohms per foot and each resistor type spark plug had a resistance value of approximately 5,000 ohms. With conventional ignition systems of this type, the distributor gap 32 would be of the order of .032 inch. To provide the combination of this invention, the width of distributor gap 32 may be progressively increased to a value at which measurements indicate no substantial further reduction of radiated interference, usually of the order of 0.090 inch.

The precise reason an increased length of distributor gap 32 reduces the radiated interference is not definitely known. It is believed, however, that increasing the width of the distributor gap provides a transitory resistance value which approaches the critical damping value of the interference generated upon distributor gap breakdown.

While a preferred embodiment of the present invention has been disclosed and described, various modifications and substitutions may be made without departing from the spirit of the invention.

We claim:

1. An internal combustion engine radio frequency radiation suppressing ignition system comprising in combination, a resistor type spark plug for each cylinder of the internal combustion engine with which the ignition system is to be used, an ignition distributor having a stationary terminal corresponding to each said resistor type spark plug and a movable terminal rotated in timed relationship with said engine and positioned to successively pass closely adjacent to each of said stationary terminals, a television-radio suppression ignition cable extending between each said stationary terminal of said ignition distributor and the corresponding said resistor type spark plug, and an air gap between said ignition distributor movable terminal and each of said stationary terminals of a width within the range of .060 inch to .250 inch at the point of nearest approach.

2. An internal combustion engine radio frequency radiation suppressing ignition system comprising in combination, a resistor type spark plug of a resistance value within the range of 1,500 to 50,000 ohms for each cylinder of the internal combustion engine with which the ignition system is to be used, an ignition distributor having a stationary terminal corresponding to each said resistor type spark plug and a movable terminal rotated in timed relationship with said engine and positioned to successively pass closely adjacent to each of said stationary terminals, a television-radio suppression ignition cable extending between each said stationary terminal of said ignition distributor and the corresponding said resistor type spark plug, and an air gap between said ignition distributor movable terminal and each of said stationary terminals of a width within the range of .060 inch to .250 inch at the point of nearest approach.

3. An internal combustion engine radio frequency radiation suppressing ignition system comprising in combination, a resistor type spark plug for each cylinder of the internal com-

bustion engine with which the ignition system is to be used, an ignition distributor having a stationary terminal corresponding to each said resistor type spark plug, a stationary center terminal and a movable terminal rotated in timed relationship with said engine and positioned to successively pass closely adjacent to each of said stationary terminals corresponding to said spark plugs and electrically connected to said stationary center terminal, an ignition coil, a television-radio suppression ignition cable extending between each said stationary terminal of said ignition distributor corresponding to said spark plugs and the corresponding said resistor type spark plug and between said stationary center terminal and said ignition coil and an air gap between said ignition distributor movable terminal and each of said stationary terminals of a width within a range of .060 inch to .250 inch at the point of nearest approach.

4. An internal combustion engine radio frequency radiation suppressing ignition system comprising in combination, a resistor type spark plug a resistance value within the range of 1,500 to 50,000 ohms for each cylinder of the internal combustion engine with which the ignition system is to be used, an ignition distributor having a stationary terminal corresponding to each said resistor type spark plug, a stationary center terminal and a movable terminal rotated in timed relationship with said engine and positioned to successively pass closely adjacent to each of said stationary terminals, corresponding to said spark plugs and electrically connected to said stationary center terminal, an ignition coil, a television-radio suppression ignition cable extending between each said stationary terminal of said ignition distributor corresponding to said spark plugs and the corresponding said resistor type spark plug and between said stationary center terminal and said ignition coil and an air gap between said ignition distributor movable terminal and each of said stationary terminals of a width within the range of .060 inch to .250 inch at the point of nearest approach.

5. A radio frequency radiation suppressing ignition system for an internal combustion engine having a plurality of spark plug receiving openings comprising in combination, an ignition coil having a secondary winding and effective during engine operation for producing a high potential pulse when each spark plug is to be energized, a distributor having a rotating contact connected to said secondary winding which sequentially registers with a plurality of stationary distributor contacts during engine operation, a spark plug in each of said openings having an insulated electrode and a resistance element of a resistance value of the order of 5,000 ohms in series therewith and a television-radio suppression ignition cable extending from each said stationary distributor contact to a respective spark plug and having a resistance value of the order of 4,000 ohms per foot, the length of each gap between said movable contact and each said stationary distributor contact when the same are in registration being an effective amount of the order of .090 inch for dampening the gap created discharge without substantially altering spark plug action.
